REVERSING CHAIN DRIVE PULLEY ASSEMBLY FOR POULTRY FEED HOPPER

Gerald L. Kitson, 9709 Belding Road,
Rockford, Mich. 49341

Original design application June 26, 1972, Ser. No. 266,488, now Patent No. 231,370. Divided and this application Apr. 16, 1974, Ser. No. 461,381

Term of patent 14 years

Int. Cl. D12—05

U.S. Cl. D55—1 C

FIG. 1

FIG. 2

FIG. 3

FIG. 5

FIG. 1 is a perspective view of a reversing chain drive pulley assembly for poultry feed hopper embodying my new design.

FIG. 2 is a top view of the reversing chain drive pulley assembly for poultry feed hopper shown in FIG. 1.

FIG. 3 is an elevation of the reversing chain drive pulley assembly for poultry feed hopper of FIG. 1 and FIG. 2, showing the side thereof not visible in FIG. 1.

FIG. 4 is an end elevation of the reversing chain drive pulley assembly for poultry feed hopper of FIG. 1, 2, and FIG. 3, showing the end thereof not visible in FIG. 1.

FIG. 5 is an elevation of the reversing chain drive pulley assembly for poultry feed hopper viewed at 5—5 in FIG. 2.

The broken line showings in the drawing are included solely for the purpose of illustration.

This application is a division of my copending application Ser. No. 266,488, filed June 26, 1972 now Patent No. D. 231,370, entitled Reversing Poultry Feed Hooper.

I claim:

The ornamental design for a reversing chain drive pulley assembly for poultry feed hopper, as shown and described.
